UNITED STATES PATENT OFFICE.

WILLIAM A. McCLELLAND, OF RIDGEWOOD, NEW JERSEY, ASSIGNOR TO THE FUCHS & LANG MANUFACTURING COMPANY, A CORPORATION OF NEW YORK.

COLLECTOR RECEPTACLE.

Application filed February 3, 1922. Serial No. 533,858.

To all whom it may concern:

Be it known that I, WILLIAM A. McCLELLAND, a citizen of the United States, residing at Ridgewood, county of Bergen, State of New Jersey, have invented certain new and useful Improvements in Collector Receptacles, of which the following is a specification.

This invention relates to collector receptacles such as are particularly adapted to be used in connection with bronzing machines employed in the finishing of lithographic prints.

An important object of the invention is to provide a receptacle particularly adapted to be used in the above mentioned connection, which is so constructed that such air currents as enter the same with suspended bronze particles may be satisfactorily relieved without loss of any portion of the bronze which is being collected or reclaimed for further use.

A further object of the invention is to provide a receptacle of the class mentioned which is simple in construction, inexpensive to manufacture, and reliable in use.

Further objects of the invention will become apparent from the following specification taken in connection with the accompanying drawings in which;

Figure 1 is a view in elevation showing the receptacle embodying my invention.

Figure 2 is a fragmental and somewhat enlarged sectional view taken on line 2—2 of Figure 1.

Figure 3 is a horizontal sectional view taken on line 3—3 of Figure 2.

Figure 4 is a fragmental and somewhat enlarged sectional view showing certain details of the sealing diaphragm.

In the drawings wherein is shown what I at present consider the preferred form of my invention, the numeral 5 indicates a receptacle preferably constructed of sheet metal which, relatively near its upper end is provided with an outwardly projecting reinforcing bead 6 adjacent to which is formed an inwardly projecting bead 7 which also serves as a reinforcement and as a shoulder or seat adapted to receive a sealing diaphragm hereinafter more particularly referred to.

The receptacle 5 is provided with a closure, indicated as a whole by the numeral 8,

which comprises a cover 9 to the overlying peripheral edge of which is secured a downwardly projecting flange or apron 10, which extends an appreciable distance below the upper edge of the receptacle 5. A pair of openings 11 and 12 are formed in the cover 9 which openings are surrounded respectively by downwardly depending flanges 13 and 14. Within the opening 11 there is arranged a pipe 15 which is adapted to communicate with an equalizing chamber or receptacle, not shown, into which the bronze particles are deposited after being removed from the surface of the lithographic prints undergoing the bronzing operation in the bronzing machine. The pipe 15 may be suitably attached to the flange 13 by any suitable means and is adapted to extend an appreciable distance into the receptacle 5 as shown in Figure 2. Within the opening 12 there is arranged a relatively short pipe 16 which is adapted to be attached by any suitable means to the flange 14. Upon the outer end of the pipe 16 there is arranged a cap ring 17 which is removable and provided with a screen 18 adapted to be held in position by a retaining ring 19 or any other suitable means. The pipe 16 extends an appreciable distance into the receptacle 5 and is provided at its lower end with a screen 20 which is similar to the screen 18 and held in position by any suitable means. The pipe 16 together with the screens 18 and 20 forms a receptacle into which is placed a filter such for example as waste 21 capable of preventing the passage of the bronze particles, which enter the receptacle with the air currents through the pipe 15 in a suspended condition, without retarding the flow or exit of air as the pressure within the receptacle tends to rise.

The closure 8 further comprises a sealing diaphragm 22 having formed therein openings 23 and 24 adjacent to which are provided upstanding flanges 25 and 26 respectively. The diaphragm 22 is suspended from the cover 9 by the pipes 15 and 16, the lower ends of which are projected through the openings 23 and 24 and secured respectively to the flanges 25 and 26 by any suitable means. At the periphery of the diaphragm 22 there is formed an angularly disposed flange 27 to which is secured a groove ring 28 which forms with the flange 27 an annular groove 29 into which is fitted a packing

ring 30 preferably of felt material. The material from which the ring 30 is formed is folded upon itself, as shown in Figure 4, and is retained within the groove 29 by 5 means of a locking ring 31. By this construction the packing ring 30 is securely retained in such a position that when the closure 8 is placed upon the receptacle 5 a tight seal is afforded between the sealing ring 22 10 and the receptacle 5 by reason of the intimate contact of the sealing ring 30 with the inwardly disposed bead or seat 7 upon which it is retained.

In use the receptacle 5 is placed in such 15 a position that the pipe, not shown, leading from the equalizing receptacle, also not shown, may be inserted into the pipe 15 whereupon the closure 8 is lowered upon a receptacle 5 to the position shown in Figure 2 thus establishing a sealed relation 20 between the diaphragm 22 and the container. As the bronze particles are driven into the equalizing chamber, not shown, they are allowed to pass therefrom through the pipe 25 15 into the receptacle 5 together with a relatively small amount of air which is not expelled into the atmosphere directly from the equalizing receptacle. By reason of the fact that the bronze particles are relatively 30 heavy they fall to the bottom of the receptacle 5 whereas the air currents which enter the receptacle are allowed to escape into the atmosphere through the relatively short pipe 16 and the filter 21 which serves to collect or prevent any of the bronze particles 35 from escaping which may fail to settle at the bottom of the receptacle.

While I have shown what I at present 40 consider the preferred form of my invention, it is to be understood that various changes in the size, shape and arrangement of parts may be resorted to without departing from the spirit of the invention or the scope of the subjoined claims.

45 I claim:

1. The combination with a receptacle having a diaphragm receiving seat, of a closure for said receptacle, said closure comprising a cover, an entrance conduit passed through 50 said cover and attached thereto, a sealing diaphragm suspended from said cover and attached to said entrance conduit, a sealing ring attached to said diaphragm and adapted to rest upon the seat of said receptacle, 55 and an exit conduit leading from the interior of said receptacle to the exterior thereof.

2. The combination with a receptacle having a diaphragm receiving seat, of a closure 60 for said receptacle, said closure comprising a cover, an exit conduit passed through said cover and attached thereto, a sealing diaphragm suspended from said cover and attached to said exit conduit, a sealing ring 65 attached to said diaphragm and adapted to

rest upon the seat of said receptacle, and an entrance conduit communicating the interior of said receptacle with the exterior thereof.

3. The combination with a receptacle having a diaphragm receiving seat, of a closure 70 for said receptacle, said closure comprising a cover having an exit opening, an entrance conduit passed through said cover and attached thereto, a sealing diaphragm suspended from said cover and attached to said entrance conduit, a sealing ring attached to said diaphragm and adapted to rest upon the seat of said receptacle, and an exit conduit passed through and secured to said 75 cover and diaphragm.

4. The combination with a receptacle having a sealing seat, of a closure for said receptacle, said closure comprising a cover having an exit opening, an entrance conduit passed through said cover and attached thereto, a sealing diaphragm suspended from said 80 cover and attached to said entrance conduit, said diaphragm being formed with a peripheral groove, and a sealing ring retained within said groove and adapted to engage the seat of said receptacle.

5. The combination with a receptacle having a sealing seat, of a closure for said receptacle, said closure comprising a cover having an exit opening, an entrance conduit passed through said cover and attached thereto, a sealing diaphragm suspended from said cover and attached to said entrance conduit, said diaphragm being formed with a peripheral groove, a sealing ring retained within said groove and adapted to engage the seat of said receptacle, and a locking ring for retaining said sealing ring anchored within said groove.

6. The combination with a receptacle, of a closure for said receptacle, said closure comprising a cover, an entrance conduit passed through said cover and attached thereto, an exit conduit passed through said cover and attached thereto, a filter material carried within said exit conduit, and a diaphragm attached to said conduits, said diaphragm being adapted to engage the wall of said receptacle.

7. The combination with a receptacle, of a closure for said receptacle, said closure comprising a cover, a sealing diaphragm suspended from said cover, said sealing diaphragm being adapted to engage the inner wall of said receptacle, an entrance conduit passed through said cover and diaphragm and attached thereto, an exit conduit passed through said cover and diaphragm and attached thereto, and a filter material carried within said exit conduit.

8. The combination with a receptacle, of a closure for said receptacle, said closure comprising a cover, a diaphragm associated with said cover, said diaphragm being provided with a peripheral groove, a sealing ring 130

locked within said groove, and means permitting ingress and egress of air currents respectively to and from said receptacle.

9. The combination with a receptacle, of a closure for said receptacle, said closure comprising a cover, an entrance conduit passed through said cover and attached thereto, an exit conduit passed through said cover and attached thereto, perforated closures for the ends of said exit conduit, packing material carried within said exit conduit, and a sealing diaphragm suspended from said closure, said diaphragm being attached to the lower ends of said conduits and adapted to engage the inner wall of said receptacle.

10. The combination with a receptacle having a sealing diaphragm seat in the form of an inwardly projecting bead, of a closure for said receptacle, said closure comprising a cover, an entrance conduit passed through said cover and attached thereto, an exit conduit passed through said cover and attached thereto, a removable perforated

closure for one end of said exit conduit, a permanently attached perforated closure for the opposite end of said conduit, a filter material carried within said exit conduit, a diaphragm suspended from said closure and attached to said conduits, said diaphragm being provided with an annular groove, a sealing ring adapted to seat upon the seat of said receptacle, and a locking ring for retaining said sealing ring within said groove.

11. The combination with a receptacle, of a closure for said receptacle, said closure comprising a cover, a diaphragm associated with said cover, said diaphragm being provided with a peripheral groove, a sealing ring located within said groove, a locking ring for retaining said sealing ring within said groove, and means permitting ingress and egress of air currents respectively to and from said receptacle.

In testimony whereof, I have affixed my signature to this specification.

WILLIAM A. McCLELLAND.
